UNITED STATES PATENT OFFICE

160,747

CASING FOR DOOR CLOSER

Herbert Charles Shead, Birmingham, England

Application August 13, 1949, Serial No. 4,486
In Great Britain May 4, 1949

Term of patent 14 years

(Cl. D10—7)

To all whom it may concern:

Be it known I, Herbert Charles Shead, a subject of the King of Great Britain, residing at 268 Hospital Street, Birmingham, England, have invented a new, original, and ornamental Design for a Casing for Door Closer, of which the following is a specification, reference being had to the accompanying drawing, forming part thereof:

Figure 1 of the drawing shows a perspective view,

Figure 2 is a plan view,

Figure 3 is a front elevation, and

Figure 4 is a side view of a casing for door closer, embodying my new design.

I claim:

The ornamental design for a casing for door closer, as shown.

HERBERT CHARLES SHEAD.
